FIG. 1

FIG. 4

FIG. 1 is a front perspective view of a combined child's bed, chest, desk and easel showing my design;

FIG. 2, a plan view with the top removed;

FIG. 3, a fragmentary perspective from the rear illustrating the parts arranged for a desk; and

FIG. 4, a fragmentary perspective from the rear illustrating the parts arranged for an easel.

The side not shown is essentially the same as the side illustrated.

This design for a child's bed is characterized by a tongue and double tree at one end of the structure, a removable cover for the bed, and a downwardly and rearwardly sloped tail gate which may be disposed in horizontal position to expose a writing surface and a magazine rack, all as illustrated.

I claim:

The ornamental design for a combined child's bed, chest, desk and easel, as shown and described.
